DENTAL CHAIR OR SIMILAR ARTICLE

John T. Armbruster, Niagara Falls, and Irwin A. Bosack,
Cheektowaga, N.Y., assignors to American Optical
Company, Southbridge, Mass.

Filed June 5, 1961, Ser. No. 65,455

Term of patent 14 years

(Cl. D15—3)

FIG. 1

FIG. 3

FIG. 2

FIG. 1 is a side elevational view of a chair showing our new design;

FIG. 2 is a rear elevational view thereof; and

FIG. 3 is a front elevational view thereof.

The dominant features of our design reside in those portions shown in full lines on the drawing.

We claim:

An ornamental design for a dental chair or similar article, as shown and described.
